AUTOMATIC SHEET FEEDING AND DELIVERY DEVICE FOR CYLINDER PRINTING PRESSES

Artur Büttner, Heidelberg, Germany, assignor to Schnellpressenfabrik Aktiengesellschaft Heidelberg, Heidelberg, Germany

Application February 4, 1939, Serial No. 254,733
In Germany February 7, 1938

3 Claims. (Cl. 271—4)

This invention relates to an improved automatically operating device for laying on and off the sheets to be printed in cylinder printing presses.

5 Hitherto the sheet feeding apparatus employed in cylinder printing presses constituted a self-contained and separately actuated device which had nothing to do with the sheet delivery device proper of the press. This device is generally 10 provided with special and independent means effecting the laying on of the sheets but is of no use for feeding of the sheets.

The present improved device is distinguished from said known devices, and excels them, by the 15 provision of a plurality of particularly designed conveying members which are movable on an axle and adapted to lay the sheets on, as well as to lay them off. In other words: the same device is utilised for both operations.

20 It is suitable to the purpose in view to design the device as a cross having four arms and being turned in steps in such a manner that when the cross is in its position of rest certain members provided at two arms of the cross take hold 25 of two sheets, whereas certain members provided at the other two of the cross arms release two sheets, and so the operation goes on in continual alternation and succession.

The respective arrangement and combination 30 of parts entails an extraordinary simplification as regards the movements requisite for laying the sheets on and off, and renders also possible a considerable increase of the working speed, in that the arm-cross need be turned only for 90 35 degrees at every print. The several phases to be carried out during the printing operation are as follows:

The first phase consists in supplying a fresh 40 sheet from the feed pile of sheets to one of the cross-arms; the preceding arm has taken hold of the sheet having been supplied prior thereto and has moved it over a laying-on table and placed it against laying-on marks whereby the sheet is registered; again simultaneously therewith a preceding arm has seized the sheet having 45 been printed prior thereto, viz., at one of the lateral rims of that sheet, and again simultaneously therewith the preceding arm is laying off the sheet printed prior thereto and places it upon the delivery pile with the printed side on the top 50 surface.

The thus designed and operated laying-on and laying-off device presents the possibility to arrange the two piles side by side at a side of the machine whereby the further advantage is ob-

tained that the composition bed, the printing cylinder, and the inking device are very conveniently accessible without necessitating lateral turning away of parts or certain devices of the machine.

Finally, another advantage also worth mentioning is that feeding of the sheets to be printed and delivering of the printed sheets is effected without the co-operation of bands or (and) rolls.

The invention is illustrated diagrammatically 10 and by way of example on the accompanying drawings on which Figure 1 is a plan view of a cylinder printing press equipped with the present improved sheet feeding and delivery device; Figure 2 shows one portion of Fig. 1 drawn to an 15 enlarged scale, and Figure 3 shows the other portion of Fig. 1 likewise drawn to an enlarged scale; Figure 4 is a vertical section on line I—I of Fig. 2; Figure 5 is likewise a vertical section on line I—I of Fig. 2, but shows certain members in another position; Fig. 6 is a vertical section on line II—II of Fig. 2; and Figure 7 is a vertical section on line III—III of Fig. 3.

Referring first to Fig. 5, it appears therefrom, 20 that the impression cylinder 1, the axle 2 of which is supported in the frame 3 of the machine, is driven by means of a pinion 5 secured to a shaft 4. The pinion meshes with a large cog-wheel 6 driving a cog-wheel 7 having the same diameter as said wheel 6 and being affixed 25 to the axle 2 the impression cylinder being driven by these members with equal speed and always in the same direction. The impression cylinder is, however, in fact, not a complete cylinder, but a cylindrical or circularly curved sector 30 which is affixed to the said axle 2, as already mentioned. This sector will be termed "impression segment" in the following part of this specification.

The said impression segment 1 is provided in 35 the usual manner with grippers 8 (Figs. 4 and 5), as well as with a clamping flap 9 and with clamping spindles 10 serving for clamping fast the usual covering 11.

Below the impression segment 1 is a composition bed 12 which bears the composition 12¹ and is reciprocated in the frame 3 by suitable means. The ink for the composition is drawn from the inking device 13 merely indicated in Fig. 1.

From the Figs. 1 and 3 it appears that the support 14 (Fig. 7) for the feed-pile 15 is arranged at a side of the frame 3 of the machine. In said frame there is journalled a vertical shaft 16 (Figs. 1 and 5) which is vertically shiftable, as well as rotatable, and a disk 17 is affixed to said shaft.

Said disk is, in the example shown, provided with four arms 17¹, 17², 17³ and 17⁴ arranged relatively to one another in angles of 90 degrees and equipped with grippers for taking hold of 5 the sheets and for conveying them. The said arms constitute a rotary cross which is turned in intervals about 90°, and always in the same direction, whereby the sheet next to be printed is conveyed from the feed pile 15 to the laying-on 10 table 18, and the printed sheet to the delivery pile 19 which is likewise arranged at a side of the machine. The support 14 of said feed pile 15 and the support (not shown) of the delivery pile 19 are controlled by known means in such 15 a manner that the first is lifted and the other is lowered in correspondence with the progression of the printing operation.

I am now going to describe the course of a sheet passing through the machine.

20 In the example illustrated in the drawings the four arms of the rotary cross are designed as grippers. The sheet to be printed is lifted off from the feed pile by means of a sucker bar 20 (Figs. 1, 3 and 7) and conveyed to that arm of 25 the cross just being located in front of said sucker bar, which may be assumed to be the arm 17¹ (Figs. 1 and 3). After this arm has seized the sheet concerned at the front edge of the same, the vertical shaft 16 is lifted (by means de- 30 scribed hereinafter) together with the arm-cross as much as requisite; the sucker bar 20 partakes in said vertical movement. Now the entire arm-cross is turned by 90 degrees whereby the sheet will be conveyed onto the laying-on table 35 18, and as soon as the sheet has been withdrawn below the sucker bar 20 which has not partaken in the rotary motion said bar is again lowered in order to suck on the next sheet. In the meantime the shaft 16 again has been lowered, to- 40 gether with the arm-cross, so that the sheet is placed in flat position upon the laying-on table 16 until it arrives at the laying-on marks 21. These marks are adjustable corresponding to the breadth of the sheet along a spindle 22. The 45 lateral registering of the sheet is effected by means of pulling or shifting marks 23.

If particularly small sheets are to be printed there is provided in the laying-on table 18 a slide 24 onto which a shiftable bracket can be 50 screwed, if requisite. Besides, if printing work of a particular kind is to be produced, such a shiftable bracket can also be attached to a rail 25 inserted into the laying-on table 18.

When the sheet to be printed has been registered upon the laying-on table it is seized by a uniformly oscillating intermediary feed gripper 26 (Figs. 4 and 5) which conveys that sheet to the rotating impression segment 1. In order to render it possible to withdraw the sheet freely 55 from the laying-on table 18, the laying-on marks 21 can be lifted a little by means of a roll-lever 27 attached to the spindle 22 bearing said marks 21. The lever 27 is controlled by a cam 28 affixed to a cam disk 29 serving to open the oscillating 60 feed grippers 26 which are normally kept closed by springs. For this purpose the axle 26¹ of these grippers 26 is supported in a rail 26² forming the stationary sheek or sheeks of said grippers, and on said axle is a roll lever 30 which abuts against 65 the cam disk 29. A link 31 hinged to this disk is controlled in a suitable manner, for instance by means of a cam (not shown), whereby said disk is oscillated as requisite for the proper operation of the mechanism in question, viz. for lifting and lowering the laying-on marks 21 and to

open the intermediary feed grippers counter to the closing action of the springs attached to them.

The gripper rail 26² is carried by lateral arms 33 secured to a shaft 32, to which is, besides, affixed, outside the frame of the machine, a toothed segment 34 which meshes with a rack 35 affixed to a guide member 36 surrounding the axle 2 of the impression segment 1. Said guide member 36 is provided with guide rolls 37 and 37¹ each contacting with the circumference of an eccentric 38 affixed to the shaft 2 of said impression segment 1. This mechanism brings about a positive shifting of the rack 35 that is guided in a straight line, as well as a vertical 15 oscillation of the intermediary grippers 26. This oscillatory motion takes place in such a manner that the grippers 26 when they are in the position shown in Fig. 5 stand opposite the grippers 8 of the impression segment 1 and are, therefore, able to transmit the sheet to the grippers 8. In order to prevent the sheet from collapsing whilst being conducted from the laying-on table 18 to the impression segment 1 there is provided at the gripper rail 26² a plurality of supports 39 arranged concentrically with respect to the oscillatory axle 32 and taking part in the oscillatory motion. The grippers 8 are kept closed in known manner by means of springs. Opening them is effected by means of a cam member 40 (Fig. 5) 30 arranged on the frame of the machine, and of a roll lever 41 secured to the gripper axle and running upon said member 40.

When the grippers 8 of the impression segment have seized the sheet, the intermediary feed grippers 26 swing again upwardly, whereas the impression segment 1 continues in its rotary motion and the printing operation is effected by the composition 12¹ while this is being moved to the left (Fig. 5).

After the printing has been done and when the impression segment 1 is in the position shown in Fig. 4, the front rim of the printed sheet is seized by a second set 42 of oscillating grippers, the common axle of these grippers 42 being supported in a gripper rail 42¹ (Fig. 4). This rail is attached at one of its ends to a lever arm 43 supported on a bolt 44 screwed into the frame of the machine. The grippers are kept closed by springs and are opened by means of a roll 50 lever 45 which when the oscillating grippers 42 are in the position shown in Fig. 4 runs upon an abutment member (not shown) and opens the grippers, so that they can extend over the sheet at the front rim of the same. Simultaneously therewith the cylinder grippers 8 are opened by the roller-lever 41 affixed to their axle and cooperating with a cam piece (not shown). As soon as the oscillating grippers 42 have seized the sheet, the arm 43 performs a 55 swinging motion together with the grippers 42 whereby the sheet is withdrawn from the impression segment 1 and pulled upon a delivery table 46. The oscillatory motion of the arm 43 is effected by means of a lever 47 affixed to the axle 44 and connected with a link 48 (Figs. 4 and 5); the other end of this link is hinged to a lever 49. This lever is supported on a bolt 50 and is at the end hinged to the link 48 provided with a roll 51. The bolt 50 is secured to the cog-wheel 6 which rotates continually, and said roll 51 engages a stationary cam 52. When the wheel 6 rotates, the oscillating grippers 42 are moved to and fro by means of the lever-mechanism just described, and at the same time the

- cam 52 regulates this oscillatory motion in such a manner that a short pause takes place in the end position (Fig. 5) of the oscillating grippers 42 and that, besides, the withdrawal of the sheet from the impression segment takes place in accurate co-incidence with the rotary speed of this segment. In order to convey the sheet to and on the delivery table 46 with a possibly short oscillatory movement and to lay it down upon a supporting surface in flat state along its entire length, said table is composed of two parts 46 and 46¹, of which the latter can be moved to and fro rectilinearly relatively to the other part 46.
- When the oscillating grippers 42, together with the sheet they have seized, have been swung over the front edge of the delivery table 46, 46¹ this latter part is moved outwardly in order to elongate the supporting surface, whereas the part 46 is and remains stationary. For shifting the part 46¹, may be with utilisation of the oscillatory movement of the feed grippers 26, a link 53 is attached to the oscillating axle 32 by means of a bolt 54; said link is connected at its other end with a lever 55. Such a lever is provided at each side of the machine on a shaft 56 and engages, by the intermediary of a link 57, a bolt 59 attached to the bottom surface of the displaceable table part 46¹.
- As soon as the printed sheet lies stretched out upon the delivery table 46, 46¹ the oscillating grippers 42 are opened in that the roll lever 45 located upon the axle of these grippers pushes upon a controlled abutment member 60 (Fig. 5).
- Now the printed sheet is seized by that gripper arm (for instance 17³) which is just in the proper position for the operation that has now to take place. The sheet is seized at one of its lateral rims and the gripper-cross rotates, but is also lifted in the below-described manner so that the gripper-arm concerned (say 17³) is withdrawn from the delivery table 46, 46¹. Owing to that rotation of the gripper-cross and to the lowering thereof which takes place simultaneously with said rotation the printed sheet is placed upon the delivery pile 19 situated at a side of the frame of the machine.
- In order to render it possible to seize also smaller sheets with an arm of the gripper-cross and to convey them to and onto the delivery pile, the sheets constituting the feed-pile must always contact at their left-hand edge with an abutment member 15¹, as indicated by dotted lines in Figs. 1 and 3.
- While the printed sheet is swung outwardly, the outer part 46¹ of the delivery table 46, 46¹ is again shifted inwardly, whereby the length of this table is reduced, so that the oscillating gripper 42 can swing back into the position shown in Fig. 4 so as to be able to seize the next printed sheet.
- The step-wise rotary movement of the gripper-cross by angles of 90 degrees can be effected, for instance, with such means as are illustrated in Fig. 6 and which are designed as follows:
- To the axle 2 of the impression segment 1 is affixed a cam disk 62 which is engaged by the roll 63 of a lever 64 turnable on a pivot 65 screwed into the frame of the machine. If the segment 1 is so designed as to perform one revolution at every print, the lever 64 makes one to-and-fro oscillation during that time. This movement is transmitted by means of a link 66 to a rack 67 guided rectilinearly in said frame. The rack 67 meshes with a toothed segment 68 which is firmly connected with a partly toothed wheel 69 and a helical-wheel 70, these three wheels rotating, therefore, simultaneously on a common axle 11. The helical-wheel 70 meshes with a second helical-wheel 72 secured to a shaft 74 supported in bearings 73, to this shaft is, furthermore, firmly affixed a long pinion 75 which meshes with a large cog-wheel 76 affixed to the vertical shaft 16 carrying the gripper-cross. The cam member 62 from which the rotary motion of the gripper-cross is drawn is so shaped that the rotary motion of the shaft 16 is initiated by the rack 67 and the speed increases from zero to a certain predetermined maximum, whereafter the partly toothed wheel 69 commences to mesh with another partly toothed cog-wheel 77 secured to the axle 2 of the impression segment 1 and rotates with the same uniform speed as said segment. The gripper-cross continues to rotate with said uniform speed until the two wheels 69 and 77 have come out of engagement, but prior thereto cog-wheel 68 has again come into engagement with the returning rack 67, the speed of which is slowly reduced until it finally becomes zero so that the cog-wheel 69 and, therefore, also the rotary motion of the gripper-cross comes to a standstill. The ratio of gearing of the wheels 75 and 76 is 1:4 so that the gripper-cross moves through an angle of 90 degrees when the wheel 75 makes one revolution.
- Lifting and lowering of the gripper-cross at every partial rotation is effected as follows:
- In the cog-wheel 6 (Fig. 6) there is a curved groove 78 into which engages a roll 79 which is attached to a bell-crank lever 80, 81 turnable on a bolt 82 screwed into the frame of the machine. A link 83 is hinged to the arm 81 of said bell-crank lever and establishes a connection with the arm 84 of a second bell-crank lever 84, 85 which is likewise turnable on a bolt projecting from the frame of the machine. The arm 85 of this second lever is designed as a fork which embraces a sleeve 86 affixed to the shaft 16 which is, therefore, not only rotatable but also axially shiftable. The long pinion 75 permits that shifting without an interruption of the meshing of the teeth concerned.
- The lifting and the lowering of the gripper-cross and the rotary movements of the same need not take place independently from one another, but may be combined, for instance in such a manner that the gripper-cross is gradually lowered while it performs a part-rotation of 90 degrees.
- The grippers 17¹, 17², 17³ and 17⁴ are each in known manner provided with two cheeks, one of which is pressed against the other by means of springs attached to the axle connecting the two cheeks with one another, said springs keeping the pairs of cheeks normally closed. Firmly secured to the axle of every pair of cheeks is a roll lever 88 (Figs. 2, 3 and 6), the rolls running on a controlled cam disk 89 (Fig. 6) whereby the grippers are opened at the proper time. The cam disk 89 does not take part in the lifting and lowering of the gripper-cross. Therefore, the grippers of the four arms are always closed when the gripper-cross is lifted.
- The manner of operation of the press is as follows:
- In the position of rest of the gripper-cross, as in Fig. 1, the cross is in its lower position, and now a sheet to be printed is conveyed from the pile 15 to the gripper arm 17¹ by means of the sucker bar 20. The gripper arm 17² has at this

time released a sheet which has been moved towards the laying-on marks 21 and is now registered. The gripper arm 17³ has seized a printed sheet at a lateral edge thereof, and the gripper arm 17⁴ has released a printed sheet which he had conveyed to the delivery pile 19. In the position of rest always two gripper arms (for instance 17¹ and 17³) take hold of two sheets, whereas the other gripper arms (for instance 17² and 17⁴) release two sheets.

Now the gripper-cross is lifted and turned by 90 degrees, whereby the arm 17¹ conveys its sheet towards and against the laying-on marks, but simultaneously therewith the gripper-cross is being lowered. During this time the previously registered sheet is conveyed to the impression segment 1 by the intermediary grippers 26, and at the same time the previously printed sheet has been withdrawn from the impression segment by the oscillating grippers 42 and deposited upon the table 46, 46'. The sheet previously placed upon that table has been removed by the gripper-arm 17³ and deposited upon the delivery-pile with the printed side upward.

There are, thus, at every cycle of the printing operation two gripper-arms provided with a sheet, of which arms the one conveys a sheet to be printed from the feed-pile to and upon the laying-on table and the other conveys a printed sheet to and upon the delivery pile. The period of time available for the rotation of 90 degrees is comparatively long, in that the rotary motion can commence already when a sheet to be registered is still laying on the laying-on table. Owing to all that the several movements can be carried out in a very quiet manner.

According to the invention suckers might be used instead of the grippers.

As according to the invention the sheets constituting the feed pile must always contact at their left hand rim with an abutment member,

so that the gripper-cross seizes the printed sheet always at the same lateral rim, the advantage is obtained that the form can always be locked up in the same edge of the chase.

I claim:

1. An automatic sheet feeding and delivery device for cylinder printing machines equipped with sheet conveying means able to perform rotary movements on a vertical axle arranged laterally of the frame of the machine and having a feed pile and a delivery pile comprising in combination, a four-armed conveyor member connected to said vertical axle, means for rotating said conveyor member intermittently in the same direction through 90 degrees at a time, said four conveyor-arms being controlled in such a manner that during each complete revolution of the conveyor member through 360 degrees each of the four arms one after the other conveys a sheet to be printed from said feed pile to the laying-on marks and seizes a printed sheet by one of its lateral edges and conveys it to said delivery pile.

2. A device as specified in claim 1 wherein the printed sheet is withdrawn from the impression cylinder and is deposited above said cylinder on a support-constituting member in such a manner that a lateral edge of said sheet can be seized by one of the four arms of the sheet-conveyor member and can be swung to and over the delivery pile.

3. A device, as specified in claim 1, wherein the support-constituting member for the printed sheet to be delivered is elongated and reduced in length alternately in correspondence with the movements of oscillating conveying means for withdrawing said sheet from the impression cylinder and conveying it to and onto said support-constituting member.

ARTUR BÜTTNER.
